COMBINATION FOOD MIXER AND CUTLERY SHARPENER

Henry J. Talge and Joseph L. Grant, Kansas City, Mo.,
and Sheldon M. Rutter, Lake Forest, Ill., assignors to
John C. Hockery, Kansas City, Mo., trustee

Application August 29, 1955, Serial No. 37,698

Term of patent 14 years

(Cl. D44—1)

Fig. 2.

Fig. 1.

Fig. 3.

Fig. 4.

Fig. 5.

Fig. 6.

Fig. 1 is a perspective view of a combination food mixer and cutlery sharpener embodying our new design;

Fig. 2 is a top plan view of same;

Fig. 3 is a side elevational view of same with the cover plate removed from the sharpening portion and the sharpening portion shown in broken lines for purposes of illustration only;

Fig. 4 is a front elevational view of same;

Fig. 5 is a rear elevational view of same; and

Fig. 6 is a bottom plan view of same.

The novel features of our design reside in the portions shown in solid lines.

We claim:

The ornamental design for a combination food mixer and cutlery sharpener, as shown and described.
